DESIGN FOR A RADIO CONTROL KNOB

Evelyne J. Fisk, Kansas City, Mo., assignor to
Crystal Products Co., Kansas City, Mo., a
copartnership

Application November 13, 1945, Serial No. 123,681

Term of patent 14 years

(Cl. D26—1)

To all whom it may concern:

Be it known, that I, Evelyne J. Fisk, a citizen
of the United States, residing at Kansas City, in
the county of Jackson and State of Missouri,
have invented a new, original, and ornamental
Design for a Radio Control Knob, of which the
following is a specification, reference being had
to the accompanying drawing, forming a part
thereof.

Fig. 1 is a side elevational view of the radio
control knob.

Fig. 2 is a face view thereof, and

Fig. 3 is a perspective view thereof.

I claim:

The ornamental design for a radio control
knob, substantially as shown.

EVELYNE J. FISK.
